U.S. PATENT DOCUMENTS

FIG. 1 is a perspective view of a mounted faucet showing our design;

D493,210 S * 7/2004 Citterio D23/238
D582,009 S * 12/2008 Citterio D23/238
D712,520 S * 9/2014 Citterio D23/255
D819,181 S * 5/2018 Citterio D23/254
D912,210 S * 3/2021 Liu D23/238
D912,212 S * 3/2021 Liu D23/238

FIG. 2 is a front elevational view;

FOREIGN PATENT DOCUMENTS

FIG. 3 is a rear elevational view;

EM 000532932-0005 7/2006
WO D060961-009 9/2002

FIG. 4 is a side elevational view;

FIG. 5 is a side elevational view;

FIG. 6 is a top plan view; and,

FIG. 7 is a bottom plan view.

The broken line disclosures in the view represents portions of a mounted faucet in which the claimed design is embodied, but which forms no part of the claimed design.
